CHARLES E. FULLER, OF OMAHA, NEBRASKA, ASSIGNOR OF ONE-HALF TO ARTHUR H. FETTERS, OF OMAHA, NEBRASKA.

STEAM-BOILER LOW-WATER SIGNAL.

1,392,682.

Specification of Letters Patent.

Patented Oct. 4, 1921.

Application filed April 16, 1920. Serial No. 374,450.

To all whom it may concern:

Be it known that I, CHARLES E. FULLER, a citizen of the United States, residing at Omaha, in the county of Douglas and State 5 of Nebraska, have invented a certain new and useful Improvement in Steam-Boiler Low-Water Signals, of which the following is a full, clear, concise, and exact description, reference being had to the accompanying 10 drawings, forming a part of this specification.

This invention relates to improvements in steam boiler low water signals.

One object of this invention is to provide 15 an apparatus for automatically indicating through audible, visual or other type of signal, the water level in a steam boiler when the same falls below a predetermined level.

More specifically, the object of this invention 20 is to provide a signaling apparatus to indicate the height of the water line in a boiler as the latter approaches low water danger mark to thereby warn those in charge and responsible for proper maintenance 25 of water level in steam boilers of a condition existing within the boiler which might otherwise escape their attention.

Another specific object of the invention is 30 to provide a signaling apparatus of the character above indicated which is especially adapted for locomotives and wherein provision is made to eliminate temporary conditions resulting from surging of the water and also wherein means are provided for 35 automatically compensating for variations in the effectiveness of the signaling apparatus that might otherwise result from the accumulation of scale deposits on those parts of the apparatus normally immersed in the 40 boiler water.

In the drawings forming a part of this specification, Figure 1 is a vertical sectional view of a portion of a locomotive boiler showing my improvements in connection therewith. Fig. 2 is a vertical sectional view at right angles to the view shown in Fig. 1 to illustrate certain details of the improved construction. And Fig. 3 is a detail sectional view of the signal proper, the same 45 being upon an enlarged scale and corresponding substantially to the section line 3—3 of Fig. 1.

In said drawing, 10 denotes the crown sheet of the locomotive, 11 the tube sheet and 12 the boiler shell proper, the latter 55 having a reinforcing plate 13 at the top thereof as shown in the drawings. In carrying out my invention, the signaling apparatus will be located adjacent the crown sheet as indicated in Fig. 2. The signaling 60 apparatus, as shown, comprises, broadly, a baffle acting tank or casing 14, a float 15 suitably mounted as hereinafter described, a whistle 16, and connections from the float to the whistle hereinafter specifically described. 65

The casing 14 may be made of any desired form and of suitable material but preferably will be of substantially box-like form open at the top and composed of sheet metal suitably fabricated. Said casing is arranged 70 to be supported within the boiler by any suitable means such as the brackets 17—17 secured to the boiler shell, said brackets extending toward each other and adapted to be united by a connecting plate 18, there 75 being interposed between said plate 18 and bracket 17, blocks 19—19 which may be of any desired thickness so as to provide for vertical adjustment, as will be understood. As clearly shown in Fig. 1, the plate 18, 80 brackets 17 and blocks 19 are securely united by a plurality of bolts and nuts 20—20. Secured to the cross support just described by the inner set of bolts 20, are two angled plates 21—21 to which the casing 14 is secured as by bolts 22, as indicated in Fig. 2. An additional bracing support 23 is employed to help sustain the casing 14, said support being preferably secured at its upper end to the boiler shell as indicated at 24 85 and to the casing 14. 90

The float 15 is preferably in the form of a hollow sealed metallic float and is rigidly mounted on a lever 25 which is pivotally mounted on an inverted U-shaped bracket 95 26 secured to the under side of the plate 18, by means of adjustable bearings 27 threaded in the depending arms of the bracket 26 as clearly shown in Fig. 1. As will be seen from Fig. 2, the lever 25 extends through 100 an opening 28 in the adjacent wall of the casing 14, said opening being such as to permit movement of the lever within the necessary limits. The opposite end of the lever

25 carries a plurality of rectangular plates 29-29 which are maintained in spaced relation by suitable spacers 20 mounted on a reduced section of said lever 25, the spacers and plates being held by the nut and washer indicated at 31. The function of the plates 29 will be described hereinafter.

- Vertically adjustably secured to the right-hand end of the lever 25, as viewed in Fig. 2, is a threaded rod 32, the same having a universal joint connection with an intermediate link 33 which in turn is connected by a universal joint to a spindle 34. The latter extends into a valve casing 35 preferably threaded into the boiler shell as indicated in the drawings. The upper end of said spindle 34 is formed into a conical valve 36 arranged to coöperate with a vertical opening 37 to normally close the latter.
- 10 The valve casing 35 is provided with chambers 38, 39, 40, 41, and 42, the steam entering the chamber 38 through suitable openings 43 in the bottom of the casing. The chambers 39 and 40 are on the under side 15 and upper side respectively of the flexible differential pressure diaphragm 44 and the latter has a relatively minute opening 45 therethrough so that steam which may leak through into the chamber 39 in small quantities will be permitted to escape to the atmosphere through the opening 46 in the valve shell.
- 20

A passage 47 provides communication from the chamber 38 to the chamber 41, it being understood that the diaphragm 44 is perforated as indicated at 48 for this purpose. A valve 49 is provided in the upper part of the casing 35 to normally prevent passage of steam from the chamber 41 to the chamber 42, said valve 49 having a depending stem 50 slidable in a suitable guide provided in the casing, the lower end of said stem normally bearing on or being located in close proximity to the diaphragm 44. A passage 51 provides communication from the chamber 42 to the whistle proper 52.

25 A suitable guiding bracket 53 is provided for the connections from the float to the whistle and small openings 54 are provided preferably in the bottom of the casing 14 for the purpose hereinafter described.

In carrying out my invention, the float and associated parts will be located a desired height above the crown sheet or other surface to be protected from the fire, the float being normally immersed in the water, the normal level of which is indicated by the water line 55 in Fig. 2.

30 From the preceding description, it will be seen, that when the float 15 is held in its uppermost position, the needle valve 36 will close the passage 37 and if by any chance a slight amount of steam should escape into the chamber 39, the opening 45

will permit relief so as to prevent actuation upwardly of the flexible diaphragm 44. Under normal conditions, it is also evident that the boiler steam pressure will be on the top of the valve 49 and hence prevent escape of steam to the whistle. When the water level falls to a predetermined minimum, the float 15 will obviously drop and withdraw the needle valve 36 so as to subject the under side of the flexible diaphragm 75 to the boiler steam pressure and on account of the greater area of the diaphragm than that of the valve 49, the latter will be elevated from its seat and steam allowed to flow to and operate the whistle proper 52, 80 thus giving audible warning to the engineer in charge that the water level has either reached or is approaching an unsafe level.

In the case of a locomotive which is subject to translation, it is evident that there will be surging of the water from time to time and to overcome the effects of these momentary conditions and prevent temporary undesired operation of the whistle, the 90 casing 14 is provided as hereinbefore described. It is evident that the bottom openings 54 therein will permit correspondence of the water level within the casing with that outside thereof, and during surging, 95 the water within the casing will not be subjected to such temporary displacements.

As is well known by those who operate boilers, practically all boiler waters contain matters in solution which are deposited in the form of scale on all parts covered by the water and hence the float 15 and immediately associated parts within the water to the right hand side of the pivot point will gradually become heavier and, if not 100 counteracted or neutralized, will sooner or later cause the float to sink or assume a lower position than initially provided for. It is to overcome this effect of the gradual accumulation of scale on the float and its 105 immediately associated parts, that I provide the neutralizing plates 29. The number and area of the plates 29 subject to scale formation will be so adjusted that their area in conjunction with the area of the adjacent lever arm, times the averaged lever arm on the plate side of the pivot is equal to the area of the float and its immediately 110 associated parts, times the averaged lever arm on the float side of the pivot. In other words, what may be termed the "area-moments" on one side of the pivot of the lever 25 are equal to the "area-moments" on the opposite side and hence accumulation of scale will not affect the balance originally 115 set up in the device and uniformity and accuracy of operation are thereby insured. This feature of my invention I consider of major importance since by it I have overcome defects present in various other types 120

of low water alarms heretofore employed and which have not given success.

As will be obvious to those skilled in the art, various changes and modifications may 5 be made in the details of construction, as for instance in obtaining the counterbalanced or neutralizing "area-moments" and in the signaling device proper. I contemplate all such changes and modifications 10 that come within the scope of the claims appended hereto.

I claim:

1. In a water level signaling apparatus, the combination with a signaling device; of 15 a member subject to scale formation from the water; operative connections between said signaling device and member by which the signaling device is adapted to be affected in accordance with the position of the member; and means, similarly subject to scale formation from the water arranged to neutralize accumulation of scale deposits on 20 said member.

2. In a boiler low water signal, the combination with a pivotally mounted member 25 adapted to be maintained in its highest position by the boiler water when of a predetermined depth or greater and to fall when the boiler water drops below said predetermined depth; of a signal including a differential pressure-controlled valve subject to 30 boiler steam pressure and a second valve; and operative connections between said second valve and member, said signal being normally maintained in a condition 35 indicative of safety when said member is in its said highest position, said second valve being positively actuated, through said connections, to produce an abnormal condition 40 indicative of danger when said member is permitted to fall.

3. In a boiler low water signal, the combination with a movably mounted member 45 adapted to be maintained in its highest position by the boiler water when the latter is of a predetermined depth or greater and to fall when the water drops below said predetermined depth; of a signaling device including, a whistle, a differential pressure-controlled diaphragm, a valve adapted to 50 close communication from the interior of the boiler to one side of said diaphragm and a second valve normally closing communication from the interior of the boiler to the 55 whistle, said second named valve being subject to action of said diaphragm to open said second named valve when the latter is subjected to the boiler steam pressure; and link and rod connections between said member 60 and said first named valve arranged to positively hold the latter in closed position when said member is in its highest position.

4. In a boiler water level signal, the combination with a signaling device, a float, and 65 operative connections between said float and

signaling device by which the condition of the latter is affected in accordance with the position of the float, said float being normally immersed in the boiler water; of means, normally also immersed in the boiler 70 water, coöperating with said float and arranged to act in opposition to the weight of the float, said means and float, with the respective parts associated therewith, comprising substantially equalized area-moments 75 subject to scale formation whereby the effective buoyancy of the float is maintained in use.

5. In a boiler low water signaling apparatus, the combination with a signaling 80 device, a float subject to scale formation from the boiler water, and operative connections between said signaling device and float by which the signaling device is adapted to be affected in accordance with the 85 position of the float; and means, similarly subject to scale formation from the boiler water, arranged to neutralize accumulation of scale deposits on the float.

6. In a water level signaling apparatus 90 for boilers subject to translation, the combination with a signaling device proper; of a member arranged to be maintained in elevated position by the boiler water when the latter is of a predetermined depth or greater 95 and to fall when the water drops below said predetermined depth; operative connections between said signaling device and member and by which the signaling device is affected in accordance with the position of 100 said member; and a casing within which said member is disposed, said casing being disposed within the main body of boiler water and having restricted openings therein providing for relatively retarded passage of the 105 water from the exterior to the interior thereof and vice versa, said restricted openings preventing emptying of the casing and fluctuation of said member when the level of the main body of boiler water outside 110 thereof temporarily falls resulting from surging.

7. In a water level signaling apparatus 115 for boilers subject to translation, such as a locomotive boiler, the combination with a signaling device proper; of a float normally immersed in the boiler water; operative connections between said float and the signaling device proper and by which the condition of the latter is affected in accordance with 120 the level of the float; a lever of the first class on one end of which said float is mounted; a baffle casing surrounding said float and also disposed within the boiler water, said casing having restricted openings in the 125 walls thereof providing for limited passage of boiler water from the exterior to the interior thereof and vice versa; and scale deposit receiving members mounted on the other arm of said lever and also normally 130

immersed in the boiler water, the effective scale deposit receiving area-moments on one side of the pivot of the lever substantially equalizing the scale deposit receiving area-moments of the lever on the opposite side of its pivot.

In witness that I claim the foregoing I have hereunto subscribed my name.

CHARLES E. FULLER.
